No. 37,036.

Patented July 12, 1904

UNITED STATES PATENT OFFICE.

PHILLIP EBELING, OF MOUNDSVILLE, WEST VIRGINIA, ASSIGNOR TO FOSTORIA GLASS COMPANY, OF MOUNDSVILLE, WEST VIRGINIA, A CORPORATION OF WEST VIRGINIA.

DESIGN FOR A GLASS VESSEL.

SPECIFICATION forming part of Design No. 37,036, dated July 12, 1904.

Application filed June 20, 1904. Serial No. 213,418. Term of patent 7 years.

To all whom it may concern:

Be it known that I, PHILLIP EBELING, a citizen of the United States, residing at Moundsville, Marshall county, West Virginia, have invented a certain new, original, and ornamental Design for a Glass Vessel, as shown in the accompanying drawings, wherein—

Figures 1, 2, and 3 are elevations of different sides of a glass vessel having the surface

ornamentation which comprises my new design.

I claim—

The ornamental design for a glass vessel, as herein shown.

PHILLIP EBELING.
